[57] CLAIM

The ornamental design for a cradle for a combined
video camera and tape recorder, as shown and de-
scribed.

DESCRIPTION

FIG. 1 is a front, top and right side perspective view of
a cradle for a combined video camera and tape recorder
showing our new design;

FIG. 2 is a front elevational view thereof;

FIG. 3 is a left side elevational view thereof;

FIG. 4 is a right side elevational view thereof;

FIG. 5 is a bottom plan view thereof;

FIG. 6 is a rear elevational view thereof; and

FIG. 7 is a front, top and right side perspective view
thereof with a pivotable cover in upright open position.
